ATTORNEY

UNITED STATES PATENT OFFICE.

WILLIAM T. BLOUNT, OF WASHINGTON, DISTRICT OF COLUMBIA, ASSIGNOR OF ONE-HALF TO WILLIAM G. BARNWELL, OF SAVANNAH, GEORGIA.

LOCK.

Application filed June 16, 1924. Serial No. 720,405.

To all whom it may concern:

Be it known that I, WILLIAM T. BLOUNT, a citizen of the United States, residing at Washington, in the District of Columbia, have invented new and useful Improvements in Locks, of which the following is a specification.

This invention relates to an improved lock, one of the objects of the invention being to provide a lock with a single bolt which is made in the form of the usual spring latch bolt with means for locking the same in projected position so that the same bolt will act as a latch bolt and a locking bolt and the use of an additional locking bolt and its associated parts are eliminated.

Another object of the invention is to provide means whereby the door or barrier cannot be unlocked from one side after it has been locked on the opposite side so that if a person should lock himself in a room another person could not unlock the door from the outside of the room.

A further object of the invention is to place the tumblers for the locking member of the bolt in the knob stem and the key holes in the knobs so that but one hole through the door is needed, this hole receiving the stem.

Another object is to eliminate a key hole extending entirely through the door and lock, thus preventing a person looking through the same, by making the tumblers in the stem solid so that they interrupt the key hole.

A further object of the invention is to make the lock applicable to doors hung on the right or left sides without requiring any change to be made in the lock.

A further object of the invention is to provide guiding means for the key for guiding it to the key hole so that the key can be readily introduced into the lock in the dark, for instance, such means also acting to prevent rain and snow from entering the key hole.

A still further object of the invention is to thread the knob on the stem so that the device will be adjustable to different thicknesses of doors and to so attach the outside knob that it cannot be removed without first loosening the inside knob.

Another object of the invention is to so arrange the parts that the lock casing can

be made very small and thus require but a small opening to be made in the door or barrier, which opening with the stem opening are the only openings to be made in the door. Thus the lock can be easily and quickly put in position.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a face view of portion of a door and its casing showing the improved lock in position.

Figure 2 is a section on line 2—2 of Figure 1.

Figure 3 is a section on line 3—3 of Figure 2.

Figure 4 is a section on line 4—4 of Figure 3.

Figures 5 and 6 are detail views of the latch bolt.

Figure 7 is a detail view of the operating member for said bolt.

Figure 8 is a section on line 8—8 of Figure 7.

Figure 9 is a plan view of the ring member which is keyed to the knob stem.

Figure 10 is a section on line 10—10 of Figure 9.

Figure 11 shows one tumbler and a portion of its sleeve.

Figure 12 shows the other tumbler and a portion of its sleeve.

Figure 13 is a view of the knob stem.

Figure 14 is a view taken at right angles to Figure 13.

Figure 15 is a section on line 15—15 of Figure 14.

Figure 16 is a view of a key used with the device.

Figure 17 is a perspective view of one of the tumblers.

Figure 18 is a section on line 18—18 of Figure 3.

Figure 19 is a plan view with the latch

bolt retracted and the other parts in normal position.

Figure 20 is a similar view but showing the latch bolt retracted by the turning of a 5 knob.

Figure 21 is a view showing the latch bolt in locking position.

Figure 22 is a sectional view through Figure 21.

10 Figures 23 and 24 show an arrangement for permitting the device to be used with but a certain key.

In these views, 1 indicates a casing which is provided with the removable plate 2 and 15 which has one end attached to a face plate 3 which is adapted to be counter sunk in the edge of a door or other barrier A. A latch bolt 4 is slidably mounted in the casing and has its beveled head passing through a hole 20 in the face plate so that it can engage the keeper 5 in the door casing B. The stem of the latch bolt is forked and passes through an opening made in a slidable member 6 and it has projections 7 at the extremities 25 of its prongs for engaging recesses 8 formed in the rear part of the front part of member 6 so that the latch bolt can move rearwardly without interference on the part of the member 6 but when said member 6 is moved rearwardly it will move the latch bolt with it 30 on account of the projections 7 engaging the recesses 8. The latch bolt is held in projected position by means of a spring 9 placed on a pin 10 extending between the prongs 35 of the bolt and passing through a projection 11 on the member 6. A cross piece 12 on the stem of the latch bolt will engage the projection 11 to limit the forward movement of the latch bolt by its spring. A spring 40 13 is connected with the forward end of the member 6 and with a pin 14 carried by the casing and tends to hold said member 6 in its forward position. The sides of the member carry balls 15 which engage the sides 45 of the casing to prevent friction between the parts in the movement of the member 6.

From the foregoing it will be seen that when the beveled end of the latch bolt strikes the keeper plate in the closing of the door 50 said latch bolt will be moved inwardly against the action of its spring until it reaches the hole in the keeper plate when the spring will force the bolt outwardly again so that it will engage the keeper opening 55 and thus hold the door in closed position. When the member 6 is moved rearwardly by turning a knob, as will be disclosed hereinafter, its forward part engaging the projections 7 of the bolt will cause the bolt to 60 be retracted and then when the knob is released the springs 9 and 13 will move the parts to a position where the latch bolt will be projected through the opening in the keeper plate.

65 The knob stem 16 is of tubular construc-

tion and has its end portions screw threaded to engage the interior screw threads of the knobs 17. The central part of the stem is provided with a notch 18 and a slot 19 extends from this notch through one end of the stem. A plurality of holes 20 are formed in the outer end of the stem for receiving a screw 21 which holds the outer knob to the stem after the same has been screwed to its proper position on the stem. The es- 70 cutcheon plate 22 is provided with a flange for covering the screw when the parts are in correct position so that the outer knob can not be removed until the inner knob is loosened sufficiently to permit the stem to be partly pulled from the door to expose the head of the screw. From this construction it will be seen that the knobs can be adjusted on the stem to fit different thicknesses of doors. The inner knob is held in its adjusted position by means of the screw 23. The inner escutcheon plate is shown at 24.

Sleeves 25 and 26 are placed in the stem and are held therein by the pins 27. The sleeve 25 is provided with a slot 28 which registers with the slot 19 in the stem and the inner end of each sleeve is spaced from the notch 18 and this inner end of each sleeve is provided with a deep notch 29 and a shallow 80 notch 30, the shallow notch of the sleeve 25 communicating with the slot 28. Tumblers 31 and 32 are placed in the inner portion of the sleeve and have their inner end parts extending into the notched part of the same. These tumblers are held in place by the sleeves and they are forced apart by the spring 33 which has its ends set in sockets 34 formed in the inner ends of the tumblers and the spring encircles a pin 35 carried by one of the tumblers. Each tumbler is provided with an ear 36 for engaging the notches 29 and 30 in the sleeves and it will be seen that when the ear engages the shallow notch 30 the tumbler will be moved inwardly to a greater extent than when it engages the deep notch 29. When it is in engagement with the deep notch the outer end of the tumbler will rest against the inner end of the sleeve. The major portion of each tumbler is of cylindrical shape to fit the stem and the outer end is provided with a key hole 37. The inner end of each tumbler is provided with a notch 38 for registering with the notch 18 in the stem and the tumbler 31 is provided with a slot or groove 39 for registering with the slot 19 in the stem.

A ring member 40 is keyed to the central part of the stem by the key 41, preferably formed on the stem, and the outer escutcheon plate is provided with a groove 42 to permit the key to pass when the stem is being inserted or removed. The ring member is composed of two ring sections 43 which are 100

connected together by the two posts 44 and which are provided with the outer flanges 45 for engaging holes in the sides of the casing. The posts of the ring member engage inwardly extending projections 46 on the member 6 so that when the ring is rotated by the turning movement of the stem the member 6 will be moved rearwardly due to the engagement of one of the projections with a post. By having two projections and two posts the member will be moved by a turning movement of the stem in either direction. Thus the latch bolt can be retracted by turning a knob in either one direction or the other and as soon as the knob is released the springs will return the parts to a position with the latch bolt projected.

A locking dog 47 is pivotally supported in the casing by means of a pin 48 and a spring 49 tends to hold the dog with its notched front end in alignment with the space between the prongs of the latch bolt. The tail 50 of this dog enters the ring member and has projections thereon for engaging the inner circumference of the two parts of the ring member and said tail enters the notch 18 and is adapted to be struck by either tumbler when the same is turned by a key and this action will move the dog to one side or the other and thus place its notched head against one of the projections 7 which is of inclined shape to fit the notch and thus prevent retraction of the latch bolt as long as the tumbler is in a position to hold the locking dog in position against the end of the latch bolt. As will be seen the locking dog will engage either prong of the latch bolt according to the position the tumbler is turned so that it is not necessary to turn the tumbler in a certain direction. The slots 19, 28 and 39 in the stem, sleeve and tumbler, respectively, will permit these parts to pass the tail of the dog, as the parts are being assembled. As will be seen each tumbler must be pushed inwardly against the action of the spring 33 to move the ear 36 out of the long slot 29 and then the tumbler is given a turning movement until the ear 36 enters the shallow notch 30 and the tumbler will then be in a position with its round wall, opposite the notch 38, in engagement with the tail of the dog and holding the dog in an inclined position as shown in either the full or dotted lines in Figure 21. In this position the latch member cannot be retracted so that the door will remain locked until the tumbler is shoved inwardly again and then turned until the ear 36 will engage the deep notch 29. Then the notch 38 will be in register with the notch 18 of the stem so that the tumbler will be out of the way of the tail of the dog and then the spring 49 will return the dog to its central position so that it will not interfere with

the retraction movement of the bolt. In order to reach the key holes in the tumblers, the knobs are provided with the key holes 51 so that a key, such as shown at 52, can be passed through the hole in the knob, through a portion of the hollow stem and into the key hole formed in the tumbler. Figures 23 and 24 show wards 53 placed on the sleeve and tumbler so that a key formed with similar wards must be used to unlock the device. It will of course be understood, however, that any form of key and socket can be used with the device.

I also form each knob with a guiding recess 54 which acts to guide the key into the hole so that it is only necessary to place the key in the recess in the knob in order to have it enter the key hole. This will facilitate the placing of the key in the hole and it can be done just as easily at night and without seeing the hole. I also prefer to make the key with a rounded end, as shown at 55, which cooperates with the curved wall of the recess to direct the key to the hole.

From the foregoing it will be seen that the lock can be easily and quickly put in place by simply making a small recess in the edge of the door to receive the lock casing and to bore a hole through the door to receive the stem. No other holes are necessary. By threading the knobs to the stem, the device can be adjusted to fit different thicknesses of doors and as the screw which fastens the outer knob to the stem is covered by the escutcheon plate this knob cannot be removed in order to disassemble the parts to unlock the door. But a single bolt is used and this serves as a latch bolt and as a locking bolt. The bolt will move inwardly in the ordinary manner when the door is shut by the engagement of its beveled head with the keeper plate and it will also be moved inwardly when a knob is turned in either direction. This latter movement results from the engagement of the post on the ring member engaging one of the projections 46 on the member 6 which moves the member 6 rearwardly and this action moves the latch bolt to retracted position. When the knob is released the springs return the parts to normal position. As long as the tumblers remain in normal position the locking dog remains in its central position and will not interfere with the movement of the latch bolt. When a tumbler is adjusted to locking position by a key the locking dog is swung over, as shown in Figure 21, which will prevent movement of the bolt so that the door cannot be opened. When the tumbler is moved to locking position its lug engaging the shallow notch will hold the tumbler in projected position and the other tumbler cannot be moved inwardly far enough to free its ear from the long notch and as the tumbler for one side

of the door cannot be reached by a key inserted in the key hole at the opposite side it will be seen that the door can only be unlocked from the same side on which it has 5 been locked. This will prevent a door from being unlocked from the outside of a room after it has been locked from the inside. As the tumblers interrupt the key hole it will not be possible for a person to look into the 10 room through the key hole and one tumbler will prevent the other tumbler from being moved in an attempt to pick the lock. The tumblers are held in their locking and unlocking positions by the ears engaging the 15 notches.

It will also be seen that the lock can be placed on any door without changing the parts as it will operate just as well on a door having its hinges on the left hand as it will 20 on a door having its hinges on the right hand side. The locking tumblers are located in the stem so that they can be easily removed and new tumblers inserted which are designed to receive a different key. This is 25 desirable where a key has been lost.

It is thought from the foregoing description that the advantages and novel features of my invention will be readily apparent.

I desire it to be understood that I may 30 make changes in the construction and in the combination and arrangement of the several parts, provided that such changes fall within the scope of the appended claims.

What I claim is:—

35 1. In combination with a lock, its bolt and the means for locking the bolt in projected position, a rotatably and slidably mounted tumbler, locking means for holding the tumbler against rotary movement, 40 spring means for holding the tumbler in engagement with its locking means and a key for sliding the tumbler out of engagement with its locking means and then rotating the tumbler to cause it to engage the bolt locking means to move the same to locking position.

50 2. In combination with a lock, its bolt and the means for locking the bolt in projected position, a pair of tumblers rotatably and slidably mounted in a part of the lock, a locking means for each tumbler for holding the same against rotary movement, spring means for holding the tumblers in engagement with the locking means and a 55 key for sliding either tumbler out of engagement with its locking means and then rotating the same to cause it to engage the bolt locking means to move the same to locking position.

60 3. A lock comprising a casing, a spring pressed bolt therein, a rotary stem in the casing, means for retracting the bolt by the rotary movement of the stem, a locking member for holding the bolt in projected position, a pair of tumblers slidably and

rotatably supported in the stem, locking means for each tumbler for holding the same against rotary movement, spring means for holding the tumblers in engagement with the locking means and a key for permitting 70 either tumbler to be moved inwardly out of engagement with its locking means and then rotated to cause it to engage the bolt locking means to move the same to locking position, the inward movement of one tumbler acting to prevent the other tumbler being disengaged from its locking means.

4. A lock comprising a casing, a spring latch bolt slidably mounted therein, a spring actuated member in the casing through 80 which the bolt passes, a projection on the bolt engaging a part of the member so that the bolt must move when the member is moved while the bolt has movement independent of the member, a knob stem passing through the casing, knobs on the stem, a member connected with the stem and engaging parts on the sliding member to retract the member by the knobs, a locking dog for holding the bolt in projected position, a pair of tumblers in the stem for moving the dog to locking position, said tumblers being rotatably and slidably mounted in the stem, spring means for holding the tumblers inactive and the stem and knobs 90 having openings therein through which a key can be introduced for actuating the tumblers to cause them to engage the dog to move the same to locking position.

5. A lock of the class described comprising a casing, a bolt slidably mounted therein, a hollow knob stem passing through the casing, means for retracting the bolt by the turning movement of the stem, a locking dog for holding the bolt in projected position, a pair of tumblers in the stem for moving the dog to locking position, said tumblers closing certain portions of the stem, a knob fastened to each end of the stem and having a key hole therein for permitting a key to be inserted in the stem to manipulate a tumbler, the manipulation of one tumbler acting to prevent movement of the second tumbler and to cause said second tumbler to act as a key guard.

6. A lock of the class described comprising a casing, a bolt slidably mounted therein, a stem passing through the casing, means for retracting the bolt by the turning movement of the stem, a locking dog in the casing for holding the bolt in projected position, a pair of tumblers in the stem for moving the dog to locking position, spring means pressing the tumblers apart, each tumbler having an ear thereon and the stem having parts provided with two pairs of notches, a pair for each ear and one notch being longer than the other, the short notch holding the tumbler in locking position and a knob connected with each end of the stem 125 130

and having a key hole therein for permitting a key to be introduced into the stem to manipulate a tumbler.

7. A lock of the class described comprising a casing, a bolt slidably mounted therein, a tubular stem passing through the casing, means for retracting the bolt by the turning movement of the stem, a locking dog for holding the bolt in projected position, a pair of cylindrical tumblers rotatably mounted in the stem for holding the dog in locking position, said tumblers having notches therein for permitting the dog to remain in neutral position, a spring press-

ing the tumblers apart, said stem having 15 parts, each of which is provided with a pair of notches, one notch being shorter than the other, an ear on each tumbler for engaging the notches of each pair, said ear and notches holding the tumbler in locking and unlocking positions, a knob connected with each end of the stem and having a key hole therein for permitting a key to be introduced into the stem to manipulate the tumbler. 20 25

In testimony whereof I affix my signature.

WILLIAM T. BLOUNT.
